US0D1046874S

(12) **United States Design Patent** (10) **Patent No.:** **US D1,046,874 S**
(45) **Date of Patent:** **** Oct. 15, 2024**

(54) **CASE FOR DISPLAY SCREEN**

(71) Applicant: **LG ELECTRONICS INC.**, Seoul (KR)

(72) Inventors: **Woosuk Park**, Seoul (KR); **Hyojin Won**, Seoul (KR); **Seunghyeop Lee**, Seoul (KR)

(73) Assignee: **LG ELECTRONICS INC.**, Seoul (KR)

(**) Term: **15 Years**

(21) Appl. No.: **35/519,162**

(22) Filed: **Nov. 28, 2022**

(80) **Hague Agreement Data**

Int. Filing Date: **Nov. 28, 2022**

Int. Reg. No.: **DM/226696**

Int. Reg. Date: **Nov. 28, 2022**

Int. Reg. Pub. Date: **Dec. 1, 2023**

(30) **Foreign Application Priority Data**

Jun. 9, 2022 (KR) 30-2022-0023005

(57) **CLAIM**

The ornamental design for a case for a display screen as shown and described.

DESCRIPTION

1.1 : Perspective

1.2 : Rear perspective view

1.3 : Front

1.4 : Back

1.5 : Left

1.6 : Top

1.7 : Reference

1.8 : Reference

1.9 : Reference

1.10 : Perspective

1.11 : Rear perspective view

1.12 : Front

1.13 : Back

1.14 : Left

1.15 : Top

1.16 : Reference

The design is characterized by a built-in handle used by pushing up the top of the case; the broken lines indicate portions of the article that form no part of the claimed design; reproductions **1.1** to **1.6** show the design in the first position; reproductions **1.10** to **1.15** show the design in the second position; right side view in the first position is omitted because it is symmetrical to the left side view in the first position, reproduction **1.5**; right side view in the second position is omitted because it is symmetrical to the left side view in the second position, reproduction **1.14**; reproduction **1.7** is a reference view shown in an environment of use with detachable stand cover for the case in the first position; reproduction **1.8** is a reference view shown in an environment of use in an alternate configuration with the detachable stand cover for the case; reproduction **1.9** is a reference view shown in an environment of use in another alternate configuration with the detachable stand cover for the case;

(Continued)

reproduction 1.16 is a reference view shown in an environment of use with detachable stand cover for the case in the second position.
